US0D1111440S

(12) **United States Design Patent** (10) **Patent No.:** **US D1,111,440 S**
(45) **Date of Patent:** **** Feb. 10, 2026**

(54) **CONTAINER**

(71) Applicant: **Wanxiang A123 Systems Corp.,**
Zhejiang (CN)

(72) Inventors: **Xingfa Zhu**, Zhejiang (CN); **Ke Xu**,
Zhejiang (CN); **Xiaofeng Feng**,
Zhejiang (CN); **Lei Zhang**, Zhejiang
(CN)

(73) Assignee: **Wanxiang A123 Systems Corp.,**
Hangzhou (CN)

(**) Term: **15 Years**

(21) Appl. No.: **29/954,013**

(22) Filed: **Jul. 25, 2024**

(30) **Foreign Application Priority Data**

Jun. 4, 2024 (CN) 202430338489.8

(51) **LOC (15) Cl.** **09-03**

(52) **U.S. Cl.**

USPC **D3/272**; D3/273

(58) **Field of Classification Search**

USPC D3/272, 273

CPC B65D 88/121; B65D 88/00

See application file for complete search history.

(57) **CLAIM**

The ornamental design for a container as shown and described.

DESCRIPTION

FIG. 1 is a top, front and right side perspective view of a container showing our new design;

FIG. 2 is a bottom, rear and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion 9 in FIG. 1; and,

FIG. 10 is an enlarged view of portion 10 in FIG. 1.

The evenly dashed broken lines in the drawings illustrate portions of the container which form no part of the claimed design.

The unevenly dashed broken lines illustrate the boundary of the enlarged views and form no part of the claimed design.

1 Claim, 10 Drawing Sheets
